UNITED STATES PATENT OFFICE

146,979

DESIGN FOR A CONDIMENT SHAKER

Norman J. Mangini, Los Angeles, Calif.

Application March 18, 1946, Serial No. 127,616

Term of patent 7 years

(Cl. D44—22)

To all whom it may concern:

Be it known that I, Norman J. Mangini, a citizen of the United States, residing at Los Angeles, in the county of Los Angeles and State of California, have invented a new, original, and ornamental Design for Condiment Shaker, of which the following is a specification, reference being had to the accompanying drawing, forming part thereof.

Fig. 1 is a perspective view of a condiment shaker embodying my new design and showing the covers in closed position;

Fig. 2 is a perspective view similar to Fig. 1 but illustrating one of the covers in open position;

Fig. 3 is a perspective view of the condiment shaker shown in Figs. 1 and 2 as viewed from the rear thereof; and

Fig. 4 is a bottom plan view of the shaker shown in Figs. 1, 2 and 3.

I claim:

The ornamental design for a condiment shaker, as shown.

NORMAN J. MANGINI.
